UNITED STATES PATENT OFFICE.

RUFUS M. STIVERS, OF NEW YORK, N. Y.

DESIGN FOR FRAME-WORK OF SLEIGHS.

SPECIFICATION forming part of Design No. 11,944, dated August 17, 1880.

Application filed April 27, 1880. Term of patent 7 years.

To all whom it may concern:

Be it known that I, RUFUS M. STIVERS, a citizen of the United States, residing at New York city, in the county and State of New York, have invented and produced a new and original Design for a Finish to the Body and Frame-Work of Sleighs and other Vehicles on Runners, of which the following is a specification, reference being had to the accompanying drawings, forming part thereof.

Figure 1 is a side elevation of the sleigh. Fig. 2 is a top view of the frame-work with the body removed, showing form of the spring. Fig. 3 is an end view, showing the relative position of the body and the side finish. Fig. 4 is an enlarged view of the side finish with a portion of the body.

In the figures, A is the body of the sleigh. B is the frame-work or running-gear. a is the ornamental finish, and a' the extension of same to the dash-board, called the "connecting-strip;" b, the knees; c, the cross-bars; d, the spring; e, the runners; f, the braces; g, the scraper, and h the dash-board.

This invention relates to a new ornamental design for a finish to the frame-work and body of sleighs and vehicles on runners; and it consists in extending the ends of the knees b a few inches above the cross-bars and placing the ornamental finish upon the top of the cross-bars by tenon and mortise or otherwise, and connecting it with the bow of the runners near

the lower part of the dash-board by the connecting-strip, which is a part of the ornamental finish.

The body is placed upon the spring, which rests upon the cross-bars, and this finish covers, but is not connected with, the lower edge of the body.

Heretofore the knees of the frame-work of sleighs have been framed into the cross-bars at the top of the knees, the bottom of the body resting on the cross-bars, and not permitting the inserting of the spring without carrying the body away from the knees and cross-bars, and without ornamental finish, except upon the body of the sleigh.

The width of the finish and connecting-strip is varied according to the size of the sleigh and strength required by the connecting-strip. The body does not extend to the dash-board, as shown in Fig. 1, and is not connected with either the finish, as shown in Fig. 3, or the connecting-strip, as shown in Fig. 1.

What I claim is—

The ornamental finish a and a', carried along the tops of the knees above the connection with the cross-bars and connected with the dash-board, as shown in the annexed drawings, and herein set forth.

R. M. STIVERS.
